UNITED STATES PATENT OFFICE.

ANDREW J. JARNIG, OF SEATTLE, WASHINGTON.

SAFETY MECHANISM FOR ELEVATOR DOORS.

Application filed March 28, 1921. Serial No. 456,376.

To all whom it may concern:

Be it known that I, ANDREW J. JARNIG, a citizen of the United States, residing at Seattle, in the county of King and State of Washington, have invented a certain new and useful Improvement in Safety Mechanism for Elevator Doors, of which the following is a specification.

My invention relates to improvements in apparatus for opening and closing rolling or sliding gates or doors and the object of my improvement is to provide apparatus of this nature that may be installed on a passenger or freight elevator of the type commonly used in buildings and on the gates or doors of an elevator shaft and that may be operated in such a manner as to open and close the doors or gates of the elevator cage and the doors or gates of the elevator shaft simultaneously.

Another object is to provide apparatus of this nature that is constructed in such a manner as to make it impossible to open or close the door or gate of the elevator shaft unless the elevator cage is stopped in substantially the correct position with respect to the door of the shaft.

A further object is to provide gate and door opening and closing apparatus that will make it impossible to move the cage except when the gate or door of such cage and the corresponding gate or door of the elevator shaft are completely and entirely closed.

A further object is to provide elevator gate and door operating means that are electrically actuated thereby relieving the elevator operator of the actual work of opening and closing the doors or gates.

A further object is to provide automatic switch mechanism that will open an electric circuit and cut off the power to the electric door operating mechanism the instant the elevator doors reach a fully open or an entirely closed position.

A still further object is to provide apparatus of this nature that is strong and simple in construction, reliable and efficient in operation, not expensive to manufacture and that may be readily installed on elevator systems of the type now in common use.

With the above and other objects in view as will be apparent from the following description the invention consists in the novel

construction, adaptation and combination of parts of elevator door operating mechanism as will be more clearly hereinafter described and claimed.

In the accompanying drawings, Figure 60 1 is a view in vertical cross section of an elevator cage upon which gate or door closing mechanism constructed in accordance with this invention is installed, parts of the elevator cage being broken away and 65 the gate or door closing mechanism being shown in elevation. Fig. 2 is a fragmentary view in elevation showing gates or doors of the form commonly used for closing the doorways through which admittance is had 70 to an elevator shaft. Fig. 3 is a view partly in plan and partly in cross section showing an operative position of the elevator cage and gate or door operating mechanism with respect to the gates or doors of the elevator 75 shaft. Fig. 4 is a view in elevation showing certain parts of the gate or door closing mechanism. Fig. 5 is a view in cross section substantially on a broken line 5, 5 of Fig. 4. Fig. 6 is a view with the cover plate 80 removed of a lock that is used for locking the doors of the elevator shaft in a closed position. Fig. 7 is a view in elevation showing certain power transmission devices by which an electric motor is connected with 85 the door and gate operating mechanism. Fig. 8 is a wiring diagram showing the electrical connection with the elevator cage and with the motor that operates the devices that are used for opening and closing the 90 gates or doors.

Fig. 9 is a fragmentary view in elevation showing a modified form of door latch for the doors of the elevator shaft and Fig. 10 is a plan view of the same.

Like reference numerals designate like parts throughout the several views.

Referring to the drawings I have shown an elevator cage 10 of the usual form of construction that may be provided with a gate 100 formed of a plurality of vertical bars 11 connected in well-known manner by link members 12 and hung upon rollers 13 that roll within a channel-shaped trackway 14 in such a manner that they may be moved to 105 open or close the doorway in the front of the elevator cage.

The elevator cage 10 is arranged to be moved vertically within an elevator shaft having doorways 15 that are opened and 110

closed by rolling or sliding doors or gates 16 and 17.

The doors 16 and 17 may be of the usual well-known form of construction and may 5 be supported by hangers 18 that are connected with head blocks 19 that roll with a track-way 20 and are preferably provided with the usual mechanism, not shown, for causing the door 17 to move more slowly than the 10 door 16 so that the two doors will reach the full open or the full closed position at the same time. The doorway 15 may also be provided with a fixed panel channel 21 which has substantially the same external appearance as a door.

All of the parts hereinbefore described may be of the usual standard form of construction.

This invention comprises electrically operated mechanism for opening and closing the doors of the elevator cage and mechanical devices for engaging with and opening or closing the doors of the elevator shaft simultaneously with the opening or closing 25 of the doors of the elevator cage.

The mechanism for opening and closing the door of the elevator cage comprises a carrier block 22 having a base 23 that is slidably disposed within a suitable guideway in a track 30 member 24 that is secured to a plate 25 that extends crosswise of the elevator cage 10 adjacent the front edge thereof, see Fig. 3.

26 is a screw that extends lengthwise of the track member 24 and is threaded 35 through the block 22 in such a manner that when it is rotated the block 22 will be moved lengthwise thereon, the thread of the screw 26 being relatively steep in pitch so that the block 22 will travel at a fairly rapid speed 40 in proportion to the speed of rotation of the screw.

The inner end of the screw 26 is journaled 45 in the bearing 27 and is provided on one side of such bearing with a thrust collar 28 and on the other side with a pinion 29 that meshes with a gear wheel 30 on the shaft 31 of a motor 32. The gear wheel 30 is preferably 50 loose on the motor shaft 31 and is provided on its rear side with stop members 33 that are arranged to be engaged by an arm 34 that is 55 securely keyed to the motor shaft 31, the arrangement being such that when the motor shaft 31 is rotated the gear wheel 30 will be rotated therewith and when the direction 60 of rotation of the motor shaft 31 is reversed such shaft will turn through substantially one-half of a complete revolution before the arm 34 engages with the stop members 33 and begins to turn the gear wheel 30, thus reducing the starting strain on the motor 32 and permitting the same to pick up speed before the load is applied.

The block 22 has a vertically arranged 65 channel member 35 rigidly secured to the outer side thereof and projecting downward-

ly therefrom as shown in Figs. 4 and 5 and the lower end of the channel member 35 is rigidly connected by a bracket 36 with the bar 11 at the forward edge of the gate or door of the elevator cage. The side flanges 70 of the channel member 35 are preferably curved outwardly at both ends as shown at 39.

The door 16 of the elevator shaft is provided in its upper corner and adjacent its 75 forward edge with a latch mechanism that is disposed within a housing 37 and that comprises a vertically movable bolt 38 that is arranged to be engaged and held by a hook 40 that is yieldingly mounted within a casting 41 that is secured to the wall or frame of the elevator shaft.

The upper end of the bolt 38 is inclined as 80 at 42 and is arranged to be engaged by a similarly inclined surface 43 on the end of the hook 40 so that as the door 16 is closed the hook 40 will be raised by engagement of the inclined surfaces 42 and 43 and the bolt 38 will snap into engagement with the hook.

The bolt 38 is urged upwardly by a compression spring 44 and such bolt is provided on one side with rack teeth 45 that mesh with gear teeth 46 on an arm 47 that is mounted on a pivot 48 and is provided with a segment 50 that meshes with a corresponding segment 51 on a lever arm 52 that is mounted on a pivot 53.

The upper end of the lever arm 52 is provided with a lug 54 that projects outwardly through an opening 55 in the cover plate of the lock housing 37 so that the lever arm may be moved in the direction indicated by the arrow in Fig. 6 to thereby withdraw the bolt 38 from engagement with the hook member 40.

The lock housing 37 is provided with a rigid stud 56 that projects outwardly through the opening 55 in the cover plate and that serves as a stop for the lug 54 and as a means by which the door 16 may be moved as hereinafter explained.

The edge of the frame against which the door 16 of the elevator shaft strikes is preferably provided with resilient shock absorbing members 57. Similar members may also be provided on the elevator cage to absorb the shock due to the opening and closing of the door of such cage.

The motor 32 is connected by circuit wires 60 and 61 with a reversing switch 62 of any standard form of construction which reversing switch may be connected with circuit wires 63 and 64 through which electrical current may be supplied. The reversing switch 62 is connected by a link 65 with an actuating lever 66 that is fulcrumed on a pivot 67 and that is provided at its upper end with a slot 68 for the reception of a pin 70 on the end of a bar 71 that extends length-

wise alongside of the track member 24 and is connected with such track member by means of pins 72 that are rigid with the track and project through slots 73 in the bar. The bar 71 is provided near its opposite ends with upwardly projecting arms 74 and 75 that are arranged to be engaged by an outwardly projecting lug 76 on the side of the block 22 in such a manner that as the block 22 approaches either end of the screw 26 the upwardly projecting arm on that end of the bar 71 will be engaged by the lug 76 and the lever arm 66 will be moved far enough to open the reversing switch 62. As soon as the switch 62 is opened the supply of current to the motor 32 is cut off and further movement of the gates or doors is stopped.

After the reversing switch 62 has been moved into an open position the slot 68 in the end of the lever arm 66 makes it possible to close the reversing switch in one direction only but will not permit the reversing switch to be closed in the opposite direction; for instance, if the switch 62 is opened by the opening of the doors as shown in Fig. 1 then the slot 68 will permit the lever 66 to be moved to the left to swing the reversing switch into the closed position shown by full lines in Fig. 8 thereby rotating the motor 32 in the proper direction to close the doors but it will be impossible to throw the switch 62 into the position shown by dotted lines in Fig. 8 and thus bring a strain on the door opening and closing mechanism.

In the same manner if the doors are closed it will not be possible to close the switch 62 except in the proper direction to open the doors.

The reversing switch is preferably arranged so that the lower end of the lever arm 66 will always be moved in the direction in which it is desired to have the doors move in opening and closing the same.

The elevator cage is provided with the usual controller 77 by which the operator starts and stops the motor that moves the elevator vertically and for the purpose of preventing the elevator cage from being moved when the doors are open I have provided a switch comprising terminals 78 that are respectively connected with ends of the circuit wire 64 and that are arranged to be bridged by a contact member 80 on an arm 81 that is mounted on a fulcrum 82 and provided on its inner end with a roller 83 that is adapted to be engaged by an inclined lug 84 on the top of block 22. The arm 81 is normally urged into the position shown in Fig. 1 by a spring 85 to thereby open the switch and break the circuit that leads to the controller 77 but the inner end of such arm will be lifted by the lug 84 when the doors are closed thereby closing the switch and per-

mitting the controller 77 to operate in the usual manner.

In Figs. 9 and 10 I have shown a hook member 86 that corresponds to the hook 40 except that it is provided on the end with an enlarged portion 87 that projects toward the elevator cage and that is provided on its bottom side with an inclined portion 88 that may be engaged by an arm 89 on the block 22 in such manner as to lift the hook and cause it to release a catch member 90 that may be rigidly secured to an elevator door 91 that corresponds to the previously described door 16.

When the device shown in Figs. 9 and 10 is used the mechanism within the lock housing 37 may be dispensed with and a fixed lug 92 may be provided on the surface of the door 91 to be engaged by the channel member 35.

A key hole 37' may be provided in the lock housing 37 for permitting authorized persons on the outside of the elevator shaft to insert any desired form of key, not shown, for engaging a notch 38' cut in the bolt 38 to withdraw the bolt from its engagement 90 with the hook member 40 and open doors 16 and 17.

In operation when the doors of the shaft and the doors of the cage are closed the lugs 54 and 56 will be in such a position that the channel 35 will pass freely over such lugs as the elevator cage moves up and down. If the cage stops in front of a doorway in the shaft the lugs 54 and 56 on that doorway will be within the channel 35 so that if the circuit to the motor 26 is closed movement of the carriage block 22 will first unlatch the door 16 and will then move the doors 16 and 17 into an open position at the same time the doors of the cage are being opened. The provision of the switch connected with the arm 81 makes it impossible to start the cage when the doors are open so that the lugs 54 and 56 must remain within the channel member 35 and be closed simultaneously with the closing of the door of the elevator cage.

From the foregoing description taken in connection with the accompanying drawings the advantages of the construction and method of operation of this elevator door operating device will be readily apparent, but, while I have described the principle of operation of the invention together with the device which I now consider to be the best embodiment thereof, I desire to have it understood that the device shown is merely illustrative and that such changes may be resorted to as are within the scope of the following claims.

What I claim is:

1. The combination with elevator mechanism including a vertical elevator shaft having doorways provided with horizontally movable doors, and a vertically movable ele-

vator cage having a doorway provided with horizontally movable doors, of means for locking the doors of said shaft in a closed position, said means comprising a housing 5 mounted in each of said shaft doors, a casing secured to the frame of the said elevator shaft, a hook member yieldably mounted within the said casing, a bolt slidably mounted within the said housing and extending therefrom for engaging the said hook member, and means within the said housing for moving said bolt member out of engagement with the said hook member, said last mentioned means comprising racks 10 provided on one side of said bolt member, an arm pivotally mounted to one wall of the said housing, gear teeth provided on one end of said arm for meshing with said rack teeth, a segment provided at the other end 15 of said arm, a lever member pivotally mounted to the said housing wall, a segment provided at one end of the said lever member and meshing with the segment on the said arm, said lever member and said arm member being provided for moving the said bolt member vertically when the lever member is 20 swung horizontally.

2. The combination with elevator mechanism including a vertical elevator shaft having doorways provided with horizontally movable doors, and a vertically movable elevator cage having a doorway provided with horizontally movable doors, of apparatus 25 for opening and closing the doors of said cage and the doors of said shaft simultaneously, an electric motor for driving said apparatus, and automatic means for breaking the circuit to said motor at the instant said doors are in a fully open or fully closed position, said means comprising a reversing 30 switch, a bar slidably mounted on the said cage, a lever arm pivotally mounted to said cage, said lever arm operatively connecting said reversing switch with said slidably 35 mounted bar and means for operatively connecting said door opening apparatus with said slidably mounted bar for throwing the said reversing switch into its open position.

3. The combination with elevator mechanism including a vertical elevator shaft having doorways provided with horizontally movable doors, a vertically movable elevator cage having a doorway provided with a horizontally movable door, of means for 40 opening and closing said doors simultaneously, said means comprising a screw extending crosswise of the top portion of said cage, a motor for rotating said screw, a carrier block threaded on said screw and movable lengthwise thereof by rotation of said screw, and means for connecting said carrier block with said doors, automatic means 45 for breaking the circuit to said motor at the instant said doors are in their fully open or fully closed position, said means

comprising a reversing switch, a bar slidably mounted on said cage, a lever arm pivotally mounted in said cage, said lever arm operatively connecting said reversing switch with said slidably mounted bar, and means 50 for operatively connecting said carrier block with said slidably mounted bar for throwing the said reversing switch into its open position.

4. The combination with elevator mechanism including a vertical elevator shaft having doorways provided with horizontally movable doors and a vertically movable elevator cage having a doorway provided with a horizontally movable door, of means 55 for opening and closing said doors simultaneously, said means comprising a screw extending crosswise of the top portion of said cage, a motor for rotating said screw, a carrier block threaded on said screw, and movable lengthwise thereof by rotation of said screw, and means for connecting said carrier blocks with said doors, automatic means for breaking the circuit to said motor at the instant said doors are 60 in a fully open or fully closed position, said means comprising a reversing switch, a bar slidably mounted on said cage, a lever arm pivotally mounted to said cage, said lever arm operatively connecting said reversing switch with said slidably mounted bar, and means 65 for operatively connecting said carrier blocks with said slidably mounted bar for throwing the said reversing switch into its open position, said last named means comprising upwardly projecting arms carried by the slidably mounted bar, and a lug secured in said carrier block and adapted to engage said projecting arms.

5. The combination with elevator mechanism including a vertical elevator shaft having doorways provided with horizontally movable doors, and a vertically movable elevating cage having a doorway provided with a horizontally movable door, of means 70 for opening and closing said doors simultaneously, said means comprising a screw extending crosswise of the top portion of said cage, an electric motor for rotating said screw, a carrier block threaded on said screw and movable lengthwise thereof by rotation of said screw, and means for connecting said carrier blocks with said doors, a reversing switch interposed in the circuit wires of said electric motor, and means for 75 limiting the movement of said reversing switch to the direction necessary for closing the proper circuit to cause the electric motor to rotate in the opposite direction to its last direction of rotation, said last mentioned means comprising a bar slidably mounted on said cage, said bar having longitudinally extending slots formed therein, laterally projecting pins carried by said cage and adapted to engage said slot for 80

105

limiting the movement of said bar, a lever arm pivotally mounted in said cage, said lever arm having a transverse slot formed in its upper end that is adapted for engaging a pin carried by said bar to limit the movement of said lever to the direction opposite to its last direction of movement and a connection between said lever and said reversing switch.

In witness whereof, I hereunto subscribe my name this 21st day of March, A. D. 1921.

ANDREW J. JARNIG.
